UNITED STATES PATENT OFFICE.

THOMAS PODMORE, OF WILKESBARRE, PENNSYLVANIA.

ELEVATING-TRUCK.

No. 808,212.

Specification of Letters Patent.

Patented Dec. 26, 1905.

Application filed February 13, 1905. Serial No. 245,473.

To all whom it may concern:

Be it known that I, THOMAS PODMORE, a citizen of the United States, residing at Wilkesbarre, in the county of Luzerne and State of Pennsylvania, have invented certain new and useful Improvements in Elevating-Trucks; and I do declare the following to be a full, clear, and exact description of the invention, such as will enable others skilled in the art to

10 which it appertains to make and use the same.

My invention is an improved elevating-truck especially adapted for use in connection with machines for molding concrete blocks and other analogous machines for conveying 15 the blocks from the machines to the stands on which the blocks are to be dried; and my invention consists in the construction, combination, and arrangement of devices hereinafter described and claimed.

20 In the accompanying drawings, Figure 1 is a side elevation of a truck embodying my improvements, showing the upper frame thereof in lowered position in full lines and in a raised position in dotted lines. Fig. 2 is a trans- 25 verse sectional view of the same, taken on the plane indicated by the line *a a* of Fig. 1; and Fig. 3 is a detail transverse sectional view showing the construction of the truck and also showing the construction of the traveler 30 which rolls on the upper truck-frame.

The lower frame 1 of my improved truck is mounted on axles 2, which are provided with flanged wheels 3, that run on a track which extends from the molding-machine to 35 the stand or stands on which the blocks are dried. Bearings 4 are here shown as depending from the lower truck-frame 1 and in which the axles 2 are journaled. The sides 5 of the lower truck-frame are made of angle metal, 40 having inwardly-extending horizontal flanges or webs 6 at their upper sides. On the lower frame 1 of the truck is an upper frame 7, which is adapted to be raised therefrom and to be lowered thereon. The upper truck-frame 7 is 45 also here shown as made of angle metal, so that the same is formed with tracks 8 on its upper side. The upper frame 7 is connected to the lower frame 1 by means of links 9, which are disposed on the sides thereof and 50 have their upper and lower ends respectively pivotally connected to the upper and lower frames of the truck. To one end of the truck-frame 1 is pivoted a tubular guide 10, as at 11. In the said tubular guide is the rear por-

tion of a lever-handle 12, which is longitudinally 55 slideable in the tubular guide and the lower rear end of which is connected to the vertically-movable upper truck-frame 7 by means of a link 13, the upper end of which is pivotally connected to the upper truck-frame 60 7 and the lower end of which is pivotally connected to the inner end of the said lever-handle.

When the outer end of the lever-handle is depressed, the link 13 is raised, thereby caus- 65 ing the upper truck-frame 7 to be also raised, the links 9 permitting such vertical movement of the upper truck-frame and serving to also move the same longitudinally in one direction as it is being raised. Furthermore, the said 70 links 9 coact with the lever-handle 12 and link 13 to support the said upper truck-frame in its elevated position.

On the upper truck-frame is a traveler or car 14, which is adapted to be run onto the 75 molding-machine to receive the blocks mold- ed by the machine and to be run from the machine onto the tracks of the upper truck- frame, so that the said car or traveler when loaded may be carried by the truck to the 80 stand where the blocks are to be dried, the raising and lowering of the upper truck-frame facilitating the loading of the car onto the truck and the unloading or discharging of the 85 blocks from the car when the drying-stand has been reached. The said car 14 is provided on its under side at its ends with bolsters 15, to the under sides of which are secured frames 16, in which caster-wheels 17 are mounted, the said caster-wheels being adapted to travel 90 on the tracks 8 of the upper truck-frame. Said caster-wheels may be provided with ball- bearings or other suitable bearings to reduce friction. Said car 14 has a floor 18, supported by springs 19. The blocks are loaded on 95 the said spring-supported floor, and the same prevents the blocks from being injuriously jarred while being carried by the car.

From the foregoing description, taken in connection with the accompanying drawings, 100 the construction and operation of the invention will be readily understood without requiring a more extended explanation.

Various changes in the form, proportion, and the minor details of construction may be 105 resorted to without departing from the principle or sacrificing any of the advantages of this invention.

Having thus described my invention, what I claim as new, and desire to secure by Letters Patent, is—

A truck of the class described having a lower frame, an upper frame on the lower frame and adapted to be raised and lowered, links connecting the upper and lower frames together, said links serving to support the upper frame in an elevated position, a guide member pivotally connected to the lower frame, a lever-handle mounted and slidale in said guide

member, and a link connecting the lever-handle to the upper truck-frame, for the purpose set forth, substantially as described.

In testimony whereof I have hereunto set my hand in presence of two subscribing witnesses.

THOMAS PODMORE.
